UNITED STATES PATENT OFFICE.

FRANK WILLIAM GUNTON, OF LONDON, ENGLAND, ASSIGNOR TO THE WILCOX & WHITE COMPANY, OF MERIDEN, CONNECTICUT, A CORPORATION OF CONNECTICUT.

AUTOMATIC MUSICAL INSTRUMENT.

980,151.

Specification of Letters Patent. Patented Dec. 27, 1910.

Application filed April 2, 1909. Serial No. 487,498.

To all whom it may concern:

Be it known that I, FRANK WILLIAM GUNTON, a subject of the King of England, residing at London, in England, have invented 5 certain new and useful Improvements in or Relating to Automatic Musical Instruments, of which the following is a specification.

This invention relates to improvements in automatic musical instruments and has particular reference to the action of a grand piano having the automatic mechanism embodied within the case of the instrument.

In an ordinary grand piano, the hammer action is directly operated by the keys. 15 Each key is poised on a balance rail; the front of the key lies in the key-board and the rear end of each key carries or operates the lever or hopper, check and damper of the hammer action. Each key at the key-board 20 has a certain range of movement which gives rise to the necessary movement of the hammer action and when the piano is to be operated automatically, it is desirable that the "striker" of the automatic mechanism 25 should impart the same range of movement to the hammer action as the ordinary manual key. It is also desirable that the automatic mechanism should be disposed above the keys and behind the key-board. The 30 "striker" of the automatic mechanism cannot therefore conveniently be arranged to engage directly with the manual key to accomplish the desired result.

One of the chief features of this invention 35 is the employment in a piano having automatic playing mechanism of auxiliary keys or levers actuated by the automatic mechanism and also actuated by the manual key. Thus in a grand piano having automatic or 40 mechanical mechanism above the keys and behind the key-board, there may be an auxiliary key or lever actuated by said mechanical mechanism and pivoted to the rear of the balance-rail. Inasmuch as it is desirable 45 that the manual keys shall remain at rest during automatic playing, the auxiliary is loosely connected at its end (inside of the pivot point) with the manual key.

Other features of this invention will be 50 evident from the following description taken in connection with the accompanying drawing which illustrates by way of example one method of arranging automatic playing

mechanism for a grand piano in accordance with this invention, the figures showing the 55 side elevation of one manual key, a corresponding auxiliary key and hammer action. The automatic mechanism which may for example consist of a pneumatic piano player is disposed within the case of the instrument 60 just behind the key-board and above the keys. X conventionally represents a portion of the case of said player. The manual keys, auxiliary keys and actions are similar 65 in arrangement.

Referring to the drawing A is the key-frame of the grand action and B a manual key poised on a balance-rail B' in the usual manner. At a short distance to the rear of the balance-rail and above the keys is a suitable transverse rail C supporting the auxiliary keys such as D. For this purpose the rail C carries butts such as C' to which the key D is pivoted as at D'. The auxiliary key D operates a hammer action E which 75 may be of the form shown or of any other suitable type, the particular hammer action used forming no part of the present invention. The front end of the auxiliary key is so arranged as to be depressed by the 80 mechanical mechanism, as for example by the striker F of said mechanism. The auxiliary key D is pivoted at D' behind the balance-rail B' in such a way that its action upon hammer mechanism E will be substantially the same whether actuated by the 85 striker F or by the manual key. A balance spring D² is preferably provided, said spring being connected at one end to the butt C' and at the other end to the key D 90 as by means of a loop D³. The rear end of the manual key does not directly operate the hammer action but acts indirectly through the auxiliary key. Pivoted to the rear end of the key B is a member B² having 95 a screw B³ on which works an adjusting nut B⁴. The screw enters a slot D⁴ in the key D and by altering the position of the nut B⁴ on the screw B³ the auxiliary and manual keys can be relatively adjusted. 100 Any other suitable connection may be employed between the manual and auxiliary keys. The manual key is shorter than usual at the rear end and the proper balance of the key is secured by the use of a spring B⁵ arranged as shown.

It is to be understood that the details of arrangement and construction may be varied without departing from this invention.

What I claim as my invention and desire 5 to secure by Letters Patent is:—

1. In a grand piano having automatic playing mechanism, a hammer action, a manual key for operating said action, a pivot therefor arranged intermediate its 10 length, an auxiliary key, a pivot therefor arranged intermediate its length, the pivot of the auxiliary key being arranged to the rear of the pivot of the manual key, the inner end of the manual key making operative connection with the auxiliary key adjacent the extreme inner end of the latter, whereby both of said keys may impart the 15 same range of movement to said hammer action.
2. In a grand piano having automatic playing mechanism, a hammer action, a manual key for operating said action, a pivot therefor arranged intermediate its length, an auxiliary key, a pivot therefor arranged intermediate its 20 length, the pivot of the auxiliary key being arranged to the rear of the pivot of the manual key, the inner end of the manual key making operative connection with the auxiliary key adjacent the extreme inner end of the latter, whereby both of said keys may impart the 25 same range of movement to said hammer action, and adjustable means interposed between the coöperating portions of said keys.
3. In a grand piano, a hammer action, a pivoted key lever for both automatic and 30

manual operation of said action, a pivot therefor intermediate its length, a second key lever for manual operation pivoted independently of the first and, at a point in front of the pivot of the former, contacting means between the extreme rear ends of both levers, whereby a movement of the second lever will impart operative movement to the first mentioned lever and whereby movement of the first mentioned lever may be independent of the second mentioned lever.

4. In a grand piano, a hammer action, a pivoted key lever for both automatic and manual operation of said action, a pivot therefor intermediate its length, a second key lever for manual operation pivoted independently of the first for manual operation and at a point in front of the pivot of the former, a connection between the rear ends of both levers whereby a movement of the second lever will impart operative movement to the first mentioned lever and whereby movement of the first mentioned lever may be independent of the second mentioned lever and means for holding the second mentioned lever in a position of rest during the movement of the first mentioned lever.

In testimony whereof I have signed my name to this specification in the presence of two subscribing witnesses.

FRANK WILLIAM GUNTON
